UNITED STATES PATENT OFFICE.

HENRY C. JOHNSON, OF MEADVILLE, PENNSYLVANIA.

ELECTRIC SHOULDER-BRACE.

SPECIFICATION forming part of Letters Patent No. 240,726, dated April 26, 1881.

Application filed December 3, 1880. (No model.)

To all whom it may concern:

Be it known that I, HENRY CLAY JOHNSON, a citizen of the United States, residing at Meadville, in the county of Crawford and State 5 of Pennsylvania, have invented Improvements in Electric Shoulder-Braces and Chest-Expanders, of which the following is a specification.

The subject of my invention is a shoulder-brace and chest-expander consisting of a flat 10 spring, which may be of steel, wood, or other material, adapted to be laid horizontally across the shoulder-blades and attached at its ends by straps to the shoulders, the said spring containing or holding suitable bodies of metal having positive and negative relations, to which 15 are connected insulated wires of any desired length extending from the battery thus formed to the ends of the spring, thence through or by way of the shoulder-straps to the sides of 20 the body or front of the shoulders, where they receive disks or plates of metal hanging loosely from the straps, or so adjusted as to be placed in contact with any part of the person, so as to complete the electric circuit at any desired 25 point through the body of the wearer.

In order that the invention may be fully understood, I will proceed to describe it in detail with reference to the accompanying drawings, in which—

30 Figure 1 is a rear view of the apparatus. Fig. 2 is a front perspective view of the same.

A represents a bar or plate of either metal or wood, of suitable dimensions to rest against the back of the person, across the shoulder-blades, extending to the rear of the shoulders, and pierced near its extremities with slits *a a* 35 for the reception of the shoulder-straps B B, by which the spring plate or bar is fastened to the person.

40 C D are electro-galvanic metallic plates, which may be copper and zinc, but are preferably antimony and bismuth. These plates are protected from contact with the body by an insulating disk or plate, E, of rubber, glass, 45 or other non-conducting material placed beneath or in front of them—that is to say, between the galvanic or thermo-electric battery formed by the plates C D and the person.

F G represent insulated copper wires, of any 50 required length, extending from the respective plates C D, one to each end of the spring bar or plate A, thence through one of the slots

a at the end of the plate or bar, whence they are conducted by the shoulder-straps B B to the sides or front of the person, where they 55 pass through the said straps, leaving exposed or projecting ends, to which are suspended freely disks or plates of metal, H H, adapted to fall against and in contact with the skin, or adjusted to any parts, so that a complete 60 electric current will be formed through the body of the wearer at any desired point, as before stated.

In order to provide for varying the length of the conducting-wires and permit the contact-plates H H to be applied to any part of the person the covered wires F G are coiled on a reel, I, the naked ends of the wires being electrically connected with the respective plates C D in any effective manner—as, for example, 65 by passing them through or attaching them to platinum or other conducting-gudgeons J J, which are insulated from each other, but connected by the metallic reel-bearings K K with the respective plates C D.

The representations of the reel and its bearings are intended only to illustrate a mode of affording extension to the conducting-wires. In practice the particular mode of mounting the wires will be varied as required, and the 80 parts may be so proportioned as to avoid any objectionable projection from the surface of the brace-bar A.

Having thus described my invention, what I claim as new, and desire to secure by Letters Patent, is—

1. The shoulder-brace consisting of a flat bar or plate adapted to bear transversely against the shoulder-blades, connected with the shoulders by suitable straps, and provided 90 with an electric, galvanic, or thermo-electric battery, substantially as set forth.

2. The combination of the spring bar or plate A, battery C D, and insulating pad or plate E, substantially as set forth.

3. The combination of the bar or plate A, straps B, battery C D, conducting-wires F G, and metallic plates H H, substantially as and for the purposes set forth.

HENRY C. JOHNSON.
